SCRAPER

Harry G. Bingley, Southbridge, Mass., assignor to
Hyde Manufacturing Company, Southbridge,
Mass., a corporation of Massachusetts

Application October 29, 1942, Serial No. 463,799

11 Claims. (Cl. 30—171)

This invention relates to improvements in scrapers, for wood, floors, paint, etc., and the objects of the invention include the provision of new and improved blade holding devices comprising an efficient resilient blade holding means which provides a quick release for changing blades by a simple manual pressing or squeezing action; the provision of a resilient blade holding means which obviates the necessity of using the usual bolt or screw-type blade holders and clamping means as exemplified in the prior art; and the provision of a simple, easily manufactured wood scraper or the like embodying an efficient and firm blade clamping means which yet is capable of instant blade release without the use of tools, screws, or other relatively cumbersome and slowly operated blade holding clamping means or fasteners.

Further objects of the invention include the provision of a wood scraper or the like having a handle and a blade head, the former mounting a tensioned spring which extends into a slot in the blade head and is secured to the blade holder to draw it firmly into contact with the nose of the blade head to hold a blade thereagainst; said spring being of a construction to release the blade holder from the nose of the blade head by a simple manual pressing or squeeze action on the spring; and upon release of the spring, the same automatically reverts to its former state to again clamp the blade holder against the nose of the blade head.

Other objects and advantages of the invention will appear hereinafter.

Reference is to be had to the accompanying drawing in which

Fig. 1 is a top plan view of a scraper embodying my invention;

Fig. 2 is a view in side elevation of the scraper looking in the direction of arrow 2 in Fig. 1;

Fig. 3 is a partial bottom plan view of the scraper with the blade holder removed and looking in the direction of arrow 3 in Fig. 2;

Fig. 4 is a side elevation of the blade head end of the scraper with the blade holder removed;

Fig. 5 is a top plan view of the blade holder showing it attached to the spring;

Fig. 6 is an edge view of the blade holder and spring, showing the same untensioned before assembly; and

Fig. 7 is a perspective view of a blade which may be used with the scraper.

A preferred embodiment of the invention is disclosed in the drawing and as shown comprises a wooden or the like hand grip or handle 10 shaped in general to fit the operator's hand, and having a widened forward portion 12 which may be referred to as the blade head. The blade head is provided with an inclined front surface

14 which merges into a curved surface 16, the latter in turn merging into the top surface 18 of the blade head. Surfaces 16 and 18 provide a rest for the hand of the operator to allow a downward pressure on the cutting blade during scraping actions, and it is to be particularly noted that my novel scraper has its entire top surface plain, unimpeded and uninterrupted by bolts, nuts, or any type of fasteners, and that there are no apertures or irregularities in the top surface of the scraper at any point. This provides a safe, sturdy, and easily used scraper allowing maximum efficiency and comfort to the operator.

The bottom surface 20 of the scraper handle is provided with an elongated recess 22 which extends from any convenient point as 24 forwardly approximately as far as the blade head 12, for instance to a point 26. This recess is preferably longitudinal and central of the underside of the scraper as clearly shown in Fig. 3, and by terminating at point 26, a solid blade holding portion 28, extending from the forward end of the recess and from side edge to side edge of the blade head, is provided.

A slot 30 is cut in the blade head, this slot being parallel to the top and bottom surfaces of the scraper, if desired, and extending entirely across the blade head, for ease in manufacture. Slot 30 separates surfaces 14 and 16 and extends rearwardly sufficiently to communicate with recess 22 as at 32. As so far described, the scraper body is complete and ready to receive the blade holder.

The blade holder proper comprises a sheet of material, such as metal, having a relatively long flat portion 34 and a flange 36 at an edge thereof. The flange is positioned at an angle to portion 34 corresponding to the slope of surface 14 at the nose of the blade head, and flange 36 and surface 14 provide the actual blade clamping members as illustrated in Fig. 2.

A leaf spring 38 having flat end portions 40 and 42 and a central curved portion 44 bent out of the planes of both flat end portions is provided. This spring may have its flat end portions in the same plane if desired, and this condition obtains when the parts are assembled as shown in Fig. 2, although this is not necessary to the successful operation of the device. However, I prefer to form the spring so that the flat ends are at a slight angle to each other for the purpose of providing an additional tension on the blade holder, this construction being clearly shown in Fig. 6.

Flat spring portion 42 is adapted to be secured to the bottom of recess 22 by screws 46 or by any other desired means, and in this condition the flat portion 40 is positioned in the slot 30. By reason of the shape of the spring, portion 40

resiliently bears on the top surface of the slot and portion 44 is tensioned thereby. This particular effect, however, is not as important as the tension provided by the contact of flange 36 of the holder with surface 14. With the holder secured as for instance by rivets as shown, or other means, to flat portion 40 of the spring, and thus assembled, inserted through the slot to bring the spring into the recess and flange 36 into contact with surface 14, the depending curved portion 44 of the spring is urged toward the bottom of the recess to stretch flat portion 42 to the rear of the recess while maintaining the contact of flange 36 and surface 14. The spring is then fastened to the handle as described. Obviously, upon release of the curved portion 44, a great tension is exerted by flange 36 on surface 14, and this force is powerful enough to firmly clamp blade 48 therebetween. To separate the flange and clamping surface, it is only necessary to squeeze up on or press the curved portion 44 in the direction of arrow A to urge flange 36 outwardly in the direction of the arrow B to release the blade or to allow for insertion of a blade.

The blade 48 itself is preferably provided with a longitudinal angular section as shown at 50, and this provides a resilience in the blade itself in the direction of the clamping action.

It will be seen that I have provided a simple and easily manufactured scraper having a quick release and automatic clamp for the blade, and there are no machine parts necessary except for screws 46. This makes for a cheap but sturdy and efficient long-lasting tool as described.

Having thus described my invention and the advantages thereof, I do not wish to be limited to the details herein disclosed, otherwise than as set forth in the claims, but what I claim is:

1. In a device of the class described, a handle, a blade clamping surface associated with the handle, a movable blade clamping means for cooperation with said surface to clamp a blade, and resilient means effective to normally draw the blade clamping means to the surface, said resilient means being manually temporarily distortable to move the blade clamping means from the surface.

2. A scraper comprising a body having a handle and a blade-clamping surface, a blade holder adapted to cooperate with the surface to clamp a blade therebetween, a spring secured to the blade holder, and means securing the spring to the body of the scraper, said spring being tensioned between said last named means and the blade-clamping surface.

3. A scraper comprising a body having a handle and a blade-clamping surface, a blade holder having a portion adapted to clamp a blade to said surface, a spring secured to the holder and effective to normally maintain the latter in blade clamping position, and means on said spring effective to extend the same to move the blade holder out of blade clamping position upon the application of pressure to said last named means.

4. A scraper as recited in claim 3 wherein the spring is of the leaf type and said last named means comprises a bowed portion therein.

5. A scraper comprising a body having a handle and a blade-clamping surface, a slot in said body adjacent said surface, a blade holder movably mounted in the slot for movement to and from blade clamping position, a leaf spring secured to said blade holder, said spring having a bowed

portion to provide a tension for normally holding the blade holder to the surface, said bowed portion being manually distortable to increase the tension to move the blade holder to blade un-clamping position.

6. A scraper comprising a body having a blade clamping surface, a movable blade holder to clamp a blade to said surface, an elongated spring having one end fixed to the body and the other end fixed to the blade holder, a distorted portion in said spring for applying tension to the blade holder to normally maintain the same in blade holding position, said spring being manually manipulatable at its distorted portion to increase its effective length to move the blade holder away from the blade clamping surface.

7. A scraper comprising a body having a plain uninterrupted top surface and a blade clamping surface, a blade holder to clamp a blade to said blade clamping surface, a spring for normally urging the holder to the blade clamping surface, said spring having a portion for distortion to release a clamped blade by moving the blade holder away from the blade clamping surface, said blade holder and spring being disposed completely below said top surface.

8. A scraper comprising a body having a handle and a blade clamping surface, said handle having a top and bottom surface, a recess in the bottom surface, a spring secured at one end to the scraper body and located in the recess, a blade holder secured to the spring and being adapted to be drawn up to the blade clamping surface thereby, said holder being movable, upon distortion of the spring, away from the blade clamping surface.

9. A scraper comprising a body having a blade clamping surface, a recess in said body, a slot in said body adjacent the blade clamping surface, said slot communicating with the recess, a blade holder movably mounted in the slot and having a portion adapted to cooperate with the blade clamping surface to clamp a blade, a warped spring strip secured at one end to the body in the recess, said strip having a portion in the slot secured to the blade holder, the warped portion of the strip imparting a tension on the blade holder to hold it against the blade clamping surface.

10. A scraper as recited in claim 9 wherein said spring strip may be pressed to tend to flatten its warped portion to lengthen the strip, whereby the blade holder is moved from blade clamping position.

11. A scraper comprising a body having top and bottom surfaces and a blade clamping surface, a recess in the body extending inwardly thereof from the bottom surface, a slot adjacent the blade clamping surface, said slot communicating with the recess, a bowed spring strip secured at one end to the body and located in the recess, the other end of the spring entering the slot, pressure on the bowed part of the strip effectively lengthening the latter to move the strip end in the slot to and from the blade clamping surface, a blade holder in the slot and having a portion extending out of the slot to cooperate with the blade clamping surface to clamp a blade, said strip normally maintaining the blade holder in blade clamping position, but being extensible to move the blade holder away from blade clamping position upon application of said pressure.

HARRY G. BINGLEY.
